UNITED STATES PATENT OFFICE

107,902

DESIGN FOR A TOP FOR AUTOMOTIVE VEHICLES

Lynn Brodton, Collingswood, N. J.

Application August 7, 1935, Serial No. 58,003

Term of patent 7 years

To all whom it may concern:

Be it known that I, Lynn Brodton, a citizen of the United States and a resident of Collingswood, in the county of Camden and the State of New Jersey, have invented a new, original, and ornamental Design for a Top for Automotive Vehicles, of which the following is a specification, reference being had to accompanying drawing, forming a part thereof and in which

Figure 1 is a perspective view of a top for automotive vehicles embodying my new design,

Figure 2 is a plan view thereof;

Figure 3 is a side elevation thereof,

Figure 4 is a side elevation of the top alone with rear quarter down, or in lowered position, and with a hood or boot applied thereto,

Figure 5 is a front elevation of the top, and

Figure 6 is a rear elevation of the top.

The top constituting my novel design is adapted to be applied to automobiles, boats, or similar articles.

I claim:

The ornamental design for a top for automotive vehicles as shown and described.

LYNN BRODTON.
